UNITED STATES PATENT OFFICE.

CHARLES ALLEN CUMMINGS, OF BATTLE CREEK, MICHIGAN, ASSIGNOR TO BATTLE CREEK BOX COMPANY, OF BATTLE CREEK, MICHIGAN.

CRATING OR PACKING MEANS.

1,406,615.

Specification of Letters Patent. Patented Feb. 14, 1922.

Application filed April 2, 1921. Serial No. 457,970.

To all whom it may concern:

Be it known that I, CHARLES ALLEN CUMMINGS, a citizen of the United States, residing at Battle Creek, county of Calhoun, and 5 State of Michigan, have invented certain new and useful Improvements in Crating or Packing Means, of which the following is a specification.

This invention relates to improvements 10 in crating or packing means.

The main objects of this invention are to provide an improved crating or a packing means by means of which articles of furniture are protected so that they are not likely 15 to be injured in transportation.

Second. To provide an improved crating or packing means having these advantages, which is economical and may be quickly applied to or removed from a piece of furniture. 20

Third. To provide an improved furniture crating or packing means which is comparatively light in weight and well adapted to withstand the shocks and strains to which 25 articles are likely to be subjected in transportation.

Further objects and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated 35 in the accompanying drawing, forming a part of this specification, in which:

Fig. I is a plan view of the sides of a 40 crate of the wire bound type such as I preferably employ.

Fig. II is a plan view of one of the ends thereof.

Fig. III is a bottom view of my improved crating, parts being broken away for convenience in illustration.

Fig. IV is a bottom perspective view of one of the support members.

Fig. V is a detail section on a line corresponding to line 5—5 of Fig. III.

Fig. VI is a detail transverse section on a line corresponding to line 6—6 of Figs. III and V.

In the drawing similar reference characters refer to similar parts throughout the

several views, and the sectional views are 55 taken looking in the direction of the little arrows at the ends of the section lines.

In the structure I have illustrated I show my improvements as embodied by me for the packing of chests, as A, such as cedar 60 chests. These chests are commonly of considerable dimensions and considerable expense is involved in properly packing them for shipment, and it has been found to be quite a difficult matter to pack them so that 65 they would not shuck around in the crate and thereby mar the finish.

I preferably employ a wire bound crate such as I have illustrated, comprising the bottom 1, top 2 and side walls 3, each consisting of frame bars with cross panels secured thereto, and connected by the wires 4, as is a well known practice. The side walls 5 are also formed of frame pieces and cross panels and these, when the crate is 75 erected, are secured to the frame pieces of the top and bottom by means of nails 6 driven through the frame pieces of the side walls 5 into the frame pieces of the top and bottom. 80

The wire bound crates are preferred by me on account of the rapidity with which they can be set up and also because they are well adapted to withstand the shocks and strains to which they are subjected in shipment. 85

The chest A, or other article of furniture, is secured to the support members 7 which extend across the bottom and are secured thereto by nails or other suitable means. On 90 these supports 7 are plates 8 which are secured to the article of furniture by means of the nails 9, the nails being of such length that they do not fully penetrate the bottom, as these cedar chests are intended to be made 95 moth tight.

The crate is of such dimensions that the article to be crated is supported therein entirely out of contact with the walls thereof. Suspending wires or cables 10 are passed 100 around the crate and the supports, the wires being engaged in the grooves 11 of the supports so that they cannot slip therefrom.

The corner irons 12 are arranged over the corners of the article, sheets 13 of paraffin 105 paper or other suitable material being arranged under the corner members so that they do not mar the article. The supports

are recessed at 14 to receive the turn-buckles 15 by means of which the wires or cables 10 may be tightened so that the article is clamped to the support and is suspended therefrom entirely out of contact with the walls of the crate with the crate in any position. With the article thus supported within the crate it cannot be injured by the racking of the crate and the crate being of the 10 wire bound type, it will yield when subjected to blows or shocks so that it is not likely to be broken open by such strains or shocks or the contents injured.

Further, it is not necessary to use excelsior 15 or other packing material to protect the article and the crates may be rapidly applied or removed, and with reasonable care may be used repeatedly.

While I have illustrated a turn-buckle for 20 drawing up the wires, the other means for tensioning the wires, such as wire twisters, which are well known in the wire bound box art, may be used.

I have illustrated and described my improvements as I have embodied the same for 25 the crating of chests. My improvements may however be adapted to a wide variety of articles, and it is believed that the disclosures made will enable those skilled in the 30 art to which my invention relates to adapt or apply the same as may be desired.

I claim—

1. The combination with the article to be crated, of a wire bound crate of such dimensions that the article may be supported within the crate entirely out of contact with the walls thereof, support members secured to the bottom of the article and to one wall of the crate, the ends of the support members extending beyond the sides of the article, said support members being recessed and grooved on their under sides, suspending wires passed around the article and around said support members engaging the 45 grooves thereof, said wires being under such stress as to clamp the article to said support members suspending it therefrom and out of contact with the walls of the crate with the crate in any position, the article being 50 provided at its corners with angled guards over which the wires are passed, and turn-buckles for drawing up the wires disposed in said recesses.

2. The combination with the article to be crated, of a wire bound crate of such dimensions that the article may be supported within the crate entirely out of contact with the walls thereof, support members secured to the bottom of the article and to one wall 60 of the crate, suspending wires passed around the article and around said support members, said wires being under such stress as to clamp the article to said support members suspending it therefrom and out of contact 65 with the walls of the crate with the crate

in any position, the article being provided at its corners with angled guards over which the wires are passed, and turn-buckles for drawing up the wires.

3. The combination with the article to be crated, of a wire bound crate of such dimensions that the article may be supported within the crate entirely out of contact with the walls thereof, support members secured to the bottom of the article and to the crate, 70 the ends of the support members extending beyond the sides of the article, said support members being grooved on their under sides, and suspending wires passed around the article and around said support members engaging the grooves thereof, said wires being under such stress as to clamp the article to 75 said support members suspending it therefrom and out of contact with the walls of the crate with the crate in any position. 80

4. The combination with the article to be crated, of a wire bound crate of such dimensions that the article may be supported within the crate entirely out of contact with the walls thereof, support members secured 90 to the bottom of the article and to the crate, and suspending wires passed around the article and around said support members, said wires being under such stress as to clamp the article to said support members suspending 95 it therefrom and out of contact with the walls of the crate with the crate in any position.

5. The combination of a crate of such dimensions that the article to be crated may be 100 supported within the crate entirely out of contact with the walls thereof, support members secured to the article and to the crate, suspending cables passed around the article and around said support members, said 105 cables being under such stress as to clamp the article to said support members suspending it therefrom and out of contact with the walls of the crate with the crate in any position, and means for drawing up the cables. 110

6. The combination of a crate of such dimensions that the article to be crated may be supported within the crate entirely out of contact with the walls thereof, support members secured to the article and to the 115 crate, suspending cables passed around the article and around said support members, said cables being under such stress as to clamp the article to said support members suspending it therefrom and out of contact 120 with the walls of the crate with the crate in any position.

7. The combination of a crate of such dimensions that the article to be crated may be supported within the crate entirely out of 125 contact with the walls thereof, support members secured to the article and to the crate, suspending cables passed around the article and around said support members, said cables being under such stress as to clamp 130

the article to said support members suspending it therefrom and out of contact with the walls of the crate with the crate in any position, the article being provided with 5 guards over which the cables are passed so that the cables do not contact with the article.

In witness whereof, I have hereunto set my hand and seal in the presence of two witnesses.

CHARLES ALLEN CUMMINGS. [L. S.]
